UNITED STATES PATENT OFFICE

ERASTUS WILSON, OF NEW YORK, N. Y.

WINDMILL.

SPECIFICATION forming part of Letters Patent No. 249,437, dated November 8, 1881.

Application filed July 22, 1881. (No model.)

To all whom it may concern:

Be it known that I, ERASTUS WILSON, of the city, county, and State of New York, have invented a new and useful Improvement in Windmills, of which the following is a full, clear, and exact description.

The objects of my improvements are to obtain facility in erection of the mills, durability of construction, and to avoid liability of derangement.

The invention consists in certain novel features of construction in the head-castings and other portions, as hereinafter described and claimed.

15 In the accompanying drawings, forming part of this specification, Figure 1 is a perspective view of the windmill of improved construction. Fig. 2 is a vertical section through the center of the supporting-post. Fig. 3 is a plan view of the mill; and Fig. 4 is an elevation, partially in section, of the center post in a modified form.

Similar letters of reference indicate corresponding parts.

A is the casting by which the mill is secured 25 to the supporting-post. B is the head or main casting, formed with a box, b, for the wheel-shaft. T is the wheel-hub. N is a brake-pulley cast on the wheel-hub. L is a casting hinged to head B by a pin, u, and carrying the 30 vane-arm K.

The casting A is formed with a cap-plate, a, flanged at a', which cap-plate sets upon the upper end and covers the edges of the post Q, thus securing solidity and protecting the post.

35 The head-casting B and box b are in one piece, and the casting is provided with a hollow pivot, C, consisting of a wrought-iron tube, on which the head B is cast, so as to secure a firm connection, without nuts or bolts to jar 40 loose in the working of the mill, and, further, securing equal strength at all points. The tube C extends through apertures formed in the flanges a' a² of casting A, and the head B is thus supported and may turn freely.

45 On head B is pivoted an arm, r, carrying a brake, o, beneath the pulley N. s is a collar around the box b, sustaining the arm r.

P is a lever pivoted on box b, and taking by 50 one end beneath the collar s.

d is a chain from lever P to the vane-staff

K, to which the chain is connected, so that when the wheel is turned edgewise to the wind the vane will draw the chain, move lever P, and raise the brake o into contact with pulley 55 N, thus locking the wheel.

On the inner end of the wheel-shaft is fixed a face-plate, E, provided with two holes for the crank-pin of the driver, placed at varying distances from the center, so that the stroke can 60 be varied.

F is the driver, and G the plunger. The plunger G extends through the upper part of the casting B, and is formed with a slot for a guide-bolt, k, that is fixed in the head B. The 65 end of the bolt projects into the slot of the plunger, and the plunger is thus caused to move in a straight line. The plunger is also formed with a crank-piu, f, that projects into a slot in driver F.

The casting L is formed for attachment of the vane-arm K, and the vane-arm extends at the side of head B to near the wheel-hub T. The vane-arm thus forms a lever having a long purchase for operation of the brake. The 75 hinge-pin of the casting L is provided with a coiled spring, M, that acts to retain the vane in line with the wheel-shaft.

A chain, g, connected to vane-staff K, passes over friction-rollers v to a rod, w, that extends 80 downward through the tubular plunger G. This is used for turning the wheel more or less inclined to the wind by drawing on rod w by hand to swing the vane.

When the mill is to be erected on buildings 85 the hollow center post, R, (shown in Fig. 4,) is used. This is provided with an apertured cap-plate, b', so that the plunger and pump-rod can pass through the cap and post, and the cap being covered by the head-casting 90 there will be no space for leakage.

With this construction solidity and durability are secured in all parts of the windmill. The mill can be set up by inexperienced persons, and there are no complicated parts liable to derangement.

Having thus described my invention, I claim as new and desire to secure by Letters Patent—

1. In a windmill, the arm r, carrying a brake, o, under the pulley N, pivoted to the head B, 100 and sustained by a collar, s, arranged about the box b, in combination with the lever P, piv-

oted on box *b*, taking by one end beneath the collar *s*, and connected by a chain with the vane-staff, as and for the purpose specified.

2. The combination, with the head *B*, carrying the guide-bolt *k*, and the driver *F*, having a slot, as shown, of the plunger *G*, extending through the upper part of said head, provided with a slot to receive said guide-bolt, and having a crank-pin, *f*, projecting into slot of driver, as and for the purpose specified.

3. In a windmill, the casting *L*, pivoted to and extending at the side of head nearly to the wheel-hub *T*, as described, to form a lever having a long purchase for the operation of the brake.

ERASTUS WILSON.
